US0D1103058S

(12) **United States Design Patent** (10) **Patent No.:** **US D1,103,058 S**
(45) **Date of Patent:** **** Nov. 25, 2025**

(54) **WHEEL**

(71) Applicant: **Tredit Tire & Wheel Company, Inc.**, Elkhart, IN (US)

(72) Inventor: **Andrew Wuescher**, Granger, IN (US)

(73) Assignee: **Tredit Tire & Wheel Company, Inc.**, Elkhart, IN (US)

(**) Term: **15 Years**

(21) Appl. No.: **29/928,868**

(22) Filed: **Feb. 16, 2024**

Related U.S. Application Data

(62) Division of application No. 29/845,541, filed on Jul. 8, 2022, now Pat. No. Des. 1,036,347.
